VARIABLE CAPACITY DEVICE AND CIRCUIT

Noël Meyer Rust, Chelmsford, Joseph Douglas Brailsford and Arthur Leonard Oliver, London, and John Forrest Ramsay, Chelmsford, England, assignors to Radio Corporation of America, a corporation of Delaware

Application January 9, 1940, Serial No. 313,149
In Great Britain November 12, 1938

2 Claims. (Cl. 250—40)

This invention relates to variable capacity arrangements and has for its object to provide improved and simplified apparatus wherein a variable capacity effect controllable by an applied variable E. M. F. may be obtained.

Though not limited to its application thereto the invention is particularly well suited for the obtaining of automatically variable frequency selective filters which, though not limited in application thereto are primarily intended for, and particularly suitable for use in, broadcast and other radio receivers where they may be employed to provide automatic selectivity control and/or automatic frequency control, and for the obtaining of automatically variable audio correction circuits which though not limited in application thereto are primarily intended for, and particularly suitable for use in broadcast and other radio receivers where they may be employed to provide automatic tone control and/or automatic audio disturbance elimination.

Research conducted by Messrs. Johnsen and Rahbeck and published in the I. E. E. Journal for July 1923 (vol. 61, No. 320) has shown that when a conductive foil or similar conductor is placed in close juxtaposition to a semi-conductor such as a piece of lithographic stone, agate, or the like, and a voltage is applied between the semi-conductor and the foil or the like a very substantial adhesion which varies with the applied voltage takes place between the foil or the like and the semi-conductor if the surfaces in contact are suitably polished. This effect has become known as the Johnsen-Rahbeck effect and it has been proposed to employ the said effect for various electric-mechanical conversion purposes.

The present invention in its broadest aspect uses the Johnsen-Rahbeck effect and effects similar thereto, to produce a variable capacity which may be controlled by an applied voltage.

According to this invention in its broadest aspect a variable capacity effect controlled by an applied voltage is obtained by means including a conductive body having a polished insulating surface film incorporated therein or deposited thereon in close contact with either (1) another conductive body also having a similar surface film or (2) a conductor provided with a polished surface, and electrode means which, in the case of a conductor in contact with the polished surface of the conductor may include the said conductor, are provided so as to enable the potential across the polished contacting surfaces to be controlled. Variable voltage is applied between the conduc-

tors provided for that purpose and it has been found that variation of this voltage produces a substantial variation in the capacity between one of the conductors and another, fixed, conductor in electrostatic association therewith.

According to a feature of this invention, a radio or like receiver is provided with an A. F. C. (automatic frequency control) system comprising a potential variable condenser of the nature above described incorporated in or coupled to the circuit whose tuning is to be controlled and operated by A. F. C. potential obtained from a discriminator and superimposed on a suitable polarizing voltage.

According to a second feature of this invention an automatically variable frequency selective filter comprises at least one element constituted by a condenser in accordance with the invention, and the said condenser is varied by a varying applied voltage which is obtained in dependence upon the type of control required, said condenser, by varying its value, serving to alter the characteristics of the filter in the particular manner required.

An important application of this feature of the invention is to the obtaining of automatic selectivity control in a radio receiver. When so applied the invention may be utilised to give control of such form that the acceptance band of the receiver is automatically moved away from a nearby interfering signal or, should there be two nearby interfering signals, one on each side of the normal acceptance band, the said acceptance band is automatically narrowed.

According to a third feature of this invention an automatically variable audio correction circuit comprises at least one element constituted by a condenser in accordance with the invention and said condenser is varied by a varying applied voltage which is obtained in dependence upon the type of correction, said condenser, by varying its value, serving to alter the audio response characteristics of the circuit in the particular manner required. An important application of the invention is to the obtaining of automatic tone control in a radio receiver. Another application is to the obtaining of automatic elimination of "heterodyne whistle" interference in such receivers.

In the drawings—

Fig. 14 shows the tone control circuit used in Fig. 13 with connection t_7 , and

Fig. 15 shows the tone control circuit used with connection t_8 ,

Figs. 16 and 17 show two different types of interference reduction circuits embodying the present invention.

In one way of carrying out the invention and illustrated in Figure 1 of the accompanying drawings, a variable condenser comprises a piece of slate S having one surface curved and highly polished; a piece of copper foil C' cemented or otherwise suitably fixed to a flat face of the slate; a piece of polished copper foil C'' in intimate contact with the curved surface of the slate; a fixed auxiliary electrode A spaced from the polished copper foil C'' and co-operating therewith to constitute the electrodes of the condenser; and means, represented by the source B and resistance R, for applying a variable potential between the two pieces of foil. With this arrangement it has been found that the spacing and therefore the capacity between the two electrodes which constitute the electrodes of the condenser varies with the applied potential the variation being due to movement of the polished foil (as shown by the dotted line) with respect to the curved surface of the slate.

Although the above embodiment is operable and does produce a variable condenser effect, it is not preferred because there occurs a substantial hysteresis effect. As the voltage is increased the capacity decreases but on subsequent decrease of the voltage the capacity variation does not correspond to the variation during increase of voltage but, on the other hand, the capacity remains fairly constant as the voltage is reduced and then suddenly increases rapidly with further decrease in voltage. Owing to this hysteresis effect the arrangement just described will be found unsuitable for many purposes and in general will not be found suitable for use (in manner to be described later herein) for A. F. C. purposes.

In another embodiment of this invention and illustrated in Figure 2 of the accompanying drawings, two pieces of agate or slate AS' and AS''—preferably agate—are employed and each is provided with an accurately prepared plane surface PS. The two plane surfaces are placed in contact with one another and cemented on the remaining parallel flat faces of the pieces of agate or slate are pieces of metal foil MF' and MF'' (one on each) so that the two pieces

of metal foil are parallel to one another with the two pieces of slate or agate between them. Variable potential is applied between the metal foils. With this arrangement it has been found that with a suitable voltage applied—for example a voltage of 300 or so—the capacity varies very considerably with variation of applied potential. This embodiment is considerably better than the first described embodiment from the point of view of hysteresis effect, but the power factor of the condenser is rather poor and it is difficult to produce the same results time and time again.

In the preferred embodiments of this invention the di-electric of a variable condenser in accordance therewith is constituted by a very thin insulating film on a metal surface. For example in one preferred embodiment of this feature of the invention one of the electrodes of a condenser consists of a plate of aluminium which is carefully surfaced and then provided with a very thin film of insulating material, for example a film of collodion of the order of 0.001 mm. thick or less. The other electrode of the condenser is constituted by a foil or other suitable conductor in contact with the film. A polarising voltage of 200 volts, or thereabouts is applied between the foil and the plate—i. e. the electrodes of the condenser. A substantial and reproducible variation in capacity with variation in polarising voltage is obtained, there being little hysteresis effect. Similar good results can be obtained by employing, in place of collodion coated aluminium, an aluminium electrode which is chemically oxidised to provide a thin film. Again and as illustrated in Figure 3 of the accompanying drawings, an aluminium electrode AE with an anodised surface may be employed, the other foil electrode being designated F. T' and T'' are terminals one of which passes through and makes contact with AE and the other of which with a bent strip of foil ST makes contact with F. MS' and MS'' are mica spacers and MW is a mica washer, EC is an ebonite cover and EB a base. The whole assembly is held together by a screw passing through holes in the elements, the hole in F being somewhat larger than the outside diameter of MW. A suitable thickness for the spacers and washers is 0.002". Although it is not so suitable as the arrangement of Figure 3, good results can be obtained from a condenser consisting of two-faced, anodised, aluminium plates with the anodised surfaces in contact.

The actual physical action taking place in a variable condenser in accordance with this invention is somewhat obscure, but it is believed that the phenomena utilised depend upon big attractive effects which are set up across very thin di-electric films.

A condenser in accordance with this invention and such that it is comparatively free from hysteresis effect, is very suitable for incorporation in an A. F. C. system for a radio or like receiver—for example, for a push button operated superheterodyne receiver. In push button operated superheterodyne receivers it is almost essential to provide a measure of A. F. C. in order to meet difficulties due to inaccurate tuning arising from slight errors of manufacture (in the case of a push button receiver with mechanically operating tuning gear) and variations in electrical constants (in the case of a push button receiver with purely electrical tuning apparatus). Simplifi-

cation and cheapness of construction are, of course, very important desiderata. Hitherto it has been practically essential to provide in an A. F. C. system for a receiver of the nature in question at least the following apparatus: (1) a discriminator circuit and (2) an A. F. C. valve operated by the output of the discriminator circuit and in turn producing the required tuning controlling variable reactance effect in the circuit to be controlled—usually the local oscillator tuning circuit. The present invention enables the A. F. C. valve to be dispensed with, for a suitable condenser in accordance with this invention may be incorporated in the local oscillator tuning circuit and be directly controlled by the discriminator output voltage superimposed on a suitable bias voltage.

In one form of A. F. C. system in accordance with this invention, and illustrated in Figure 4 of the accompanying drawings, the usual output or load resistance R' which constitutes the D. C. output impedance of the usual discriminator D is connected in series with a portion of a resistance R'' which is in turn connected across a suitable source of potential (not shown)—for example the high tension source of the receiver—so that a desired predetermined polarising potential is superimposed upon the potentials set up across the discriminator output resistance R' . The combined polarising and discriminator output potentials are applied across an anodised aluminium electrode condenser or other suitable condenser C in accordance with this invention and the said condenser is coupled to, so as to be in effect included in, the frequency determining circuit TC of the local oscillator of the receiver, for example, as shown the condenser is capacity coupled to the tuned grid circuit TC of a back-coupled local oscillator LO comprising the triode portion of a triode-hexode local oscillator first detector valve. In order to guard against hysteresis effect of the condenser C , arrangements may be made, such that whenever a station is changed, the voltage is made to return to normal always in the same direction. To achieve this a switch is provided that will close, and then open again, whenever a station is changed. In a push button operated superheterodyne receiver a contact CO (see Figure 5 of the accompanying drawings which also shows the invention applied to a remote (cable) controlled receiver) actuated by the latch-bar of the push-button switch used for station changing can be arranged to fulfill these conditions, and it is made momentarily to short out the condenser by connecting it as shown. By this method the controlling voltage always builds up from zero, and so the condenser C always works from the same capacity value. PB is the push button contact and LO is the local oscillator.

In an embodiment of the second feature of this invention as applied to a superheterodyne radio receiver and as illustrated in Figure 6 of the accompanying drawings, there is employed as a coupling filter between two I. F. valves 1 and 2 of said receiver, a "series rejector" type of filter comprising essentially two tuned circuits TC' and TC'' . In the anode circuit of the first (1) of the two I. F. valves is a main inductance and in the grid circuit of the second (2) of the two I. F. valves is another main inductance. These two main inductances are connected together directly at the ends remote from their associated valves and are connected to one another at their other ends through two con-

densers C' and C'' in series. Between the junction point of these two condensers and the junction point of the two main inductances are two circuits in parallel SC' and SC'' each being a series resonant circuit consisting of an inductance and a condenser in series. One of these two series circuits is resonant outside one limit of the maximum I. F. band to be passed, and the other is resonant outside the other so that these two circuits control by their tuning the sides of the characteristic curve representing the acceptance band of the filter as a whole. In accordance with this feature of this invention there is connected across the condenser in each one of these series circuits, a circuit including a variable condenser VC' and VC'' in accordance with the invention and one of the variable condensers VC' is given a positive polarising voltage and the other VC'' a negative polarising voltage. I. F. voltage is also fed to another I. F. valve 3 whose output feeds into two frequency selective filters, one FS' being responsive at or near one limiting frequency of the total I. F. band to be passed and the other FS'' being responsive at and near the other limiting frequency. The output of these filters is fed to a rectifier-resistance circuit comprising two diodes D' and D'' and two resistances RE' and RE'' . The arrangement is such that when the voltage passed by both these filters is the same the output voltage produced by the diodes is zero. Voltage from either diode is superimposed on the bias potentials on the variable condensers associated therewith, one terminal of the D. C. output resistance across which voltage from one diode occurs being connected to one terminal of one conductor and one terminal of the resistance across which voltage from the diode occurs being connected to the corresponding terminal of the other condenser (in each case through a suitable resistance) the remaining terminals of the two variable condensers being connected through a resistance R'' across which the bias potential is applied and whose centre point is connected to the centre (common junction) point of the said D. C. output resistance. Thus so long as the diode outputs are zero, the values of the variable condensers are as determined by the fixed components of bias thereon, and the coupling filter between the two I. F. valves 1 and 2 presents a normal band pass characteristic (curve A of Figure 7 of the accompanying drawings). If, however, interference occurs adjacent and to one side of the normal band pass, the output from one diode will increase relative to that from the other, the voltage across the appropriate variable condenser will be varied, the capacity value will alter and the band pass characteristic of the filter will be changed so as to move the side of the characteristic adjacent the interference further away therefrom (curves B or C of Figure 7 as the case may be). Should there be two interfering signals of more or less equal strength, one on each side of the normal band pass, the effect in the circuit described will be to change the values of both variable condensers and thereby cause the side of the normal band pass acceptance curve to approach one another giving much sharper selectivity (curve D of Figure 7). The curves of Figure 7 are not quantitative.

It is, of course, not necessary to use separate I. F. valves 1 and 3 , one to feed the coupling filter and the other to feed the filters from which the variable condensers are controlled. It is also not necessary to use two variable condensers. For example in a modification of the embodi-

ment above described and illustrated in Figure 8 of the accompanying drawings, the two series circuits SC' and SC'' which are in parallel with one another in the above described embodiment are not connected directly to the junction point of the two main inductances of the filter but are connected thereto through a third series resonant circuit SC''' tuned to the mid-band frequency. A single variable condenser VC in accordance with the invention is included in a circuit across the condenser in this third rejector circuit SC''' and is subjected to a voltage composed of a predetermined fixed bias component and a variable component derived from a double diode resistance network RE fed from two filters as hereinbefore described. In this circuit, the net voltage across RE constitutes the variable component. With this arrangement, an increase in the value of the variable condenser VC will have the effect of "sliding" the band pass characteristic in the low frequency direction while a decrease will have the effect of "sliding" it in the high frequency direction.

With fairly slight modification the two embodiments above described may be adapted to produce automatic frequency control as distinct from automatic selectivity control. For example, in the second embodiment, the filters which feed the rectifier circuits from which in turn the variable condenser is operated may be so arranged that on the departure of the produced I. F. from the mid-band frequency of the I. F. amplifier, the variable condenser changes value in a direction to alter the tuning of the coupling filter so as to accord with the said produced I. F. automatic frequency. Thus A. F. C. is obtained without variation of the local oscillator of the receiver. In other words, in this manner it is possible to obtain A. F. C. action in a superheterodyne receiver by automatically varying the effective tuning of the I. F. circuit. This is, of course, in contradistinction to present day practice in A. F. C. which has been to maintain the I. F. tuning fixed and to control the local oscillator frequency to make the produced I. F. accord with the predetermined I. F. Among the advantages of the method of the present invention is that it avoids the "ganging" errors so frequently encountered in known A. F. C. systems due to the heterodyne oscillator going out of adjustment.

In another embodiment of the invention and illustrated in Figure 9 of the accompanying drawings, a coupling filter provided between two I. F. stages is automatically controlled in dependence upon the voltage derived from a known A. V. C. (automatic volume control) system so as to control the selectivity in relation to signal strength thus to provide high fidelity reception for strong signals and high selectivity reception for weak signals. This filter comprises a pair of parallel tuned circuits TC' and TC'' having parts of the inductances thereof coupled inductively to one another. Connected across the tuning condenser in one tuned circuit is a circuit comprising a variable condenser VC' and a second similar variable condenser VC'' is similarly included in a circuit connected across the corresponding tuning condenser in the other tuned circuit. Equal and opposite biases are applied to the two variable condensers and the total voltage across each of these condensers is caused to be the algebraic sum of the bias potential and a potential derived from the A. V. C. system. In the absence of control voltage from the A. V. C. system the two tuned cir-

cuits in the filter have their coupling adjusted just below the optimum coupling at which "single peak" response is obtained. If the A. V. C. voltage increases the voltage across one variable condenser is increased and that across the other decreased with the result that the resonant frequencies of the two coupled tuned circuits are staggered in opposite directions and a broad response curve with reduced gain is obtained.

The invention is not limited to the particular filter circuits described. For example another filter of variable selectivity and illustrated in Figure 10 of the accompanying drawings, comprises a pair of main inductances connected together at one end and a pair of condensers each connected at one end to the end of one or other of the main inductances, the other ends of said condenser being connected through a further condenser C'' to the junction point of the inductances. The elements thus far enumerated constitute tuned circuits TC' and TC'' . Yet another condenser C' is connected between taps (which may be variable) on the two main inductances and a variable condenser VC' in accordance with the invention hereinbefore referred to is included in circuit across this last mentioned condenser a similar variable condenser VC'' being likewise included in a circuit across the condenser which is connected to the junction point of the two main inductances. Equal and opposite polarising potentials are applied from a source represented by resistance R'' to the two variable condensers, the total voltage across each condenser being made up of a permanent bias component together with a control voltage obtained in any of the ways already described and applied by way of terminals T and B. With this arrangement, increase of one of the variable condensers will cause a widening of the band pass in a direction away to one side of the mid-band frequency (see curves 1, 2, 3, of Figure 11) while increase of the other variable condenser will cause a similar widening of the band pass in the other direction. By providing an inductance in parallel with the condenser C' between the tapping points and also providing another inductance in series with the condenser C'' which is connected at one end to the common point of the two main inductances so that the two circuits including the voltage variable condensers VC' and VC'' are respectively of the parallel resonant and series resonant types, it is possible to obtain a larger range of variation with a similar range of capacity variation than would otherwise be the case.

It is not necessary in automatic selectivity control circuits, to provide separate discriminator circuits to provide the voltage for operating the variable condenser or condensers. For example, and as shown in Figure 12, in an I. F. filter designed for a superheterodyne receiver for a predetermined I. F. of, say, 450 kc. there might be employed in the filter two "dip" circuits, one resonant at 440 kc. and the other at 460 kc. Said filter could comprise in one line and in the order stated two inductances $L'1$ and $L'2$, a condenser C and two more inductances $L''1$ and $L''2$, the junction points between the pairs of the inductances being connected to the other line through further condensers C' and C'' . The two ends of said one line are connected to the other line (in each case) through a condenser and the two inductances forming each pair are so arranged that there is positive mutual coupling between them. Automatic control of such a filter could be ob-

tained by connecting a diode D' and D'' across each of the condensers C' and C'' connected to the inductance junction points, and superimposing the rectified voltages from these diodes upon equal and opposite bias potentials applied from a source represented by resistance R'' to two voltage variable condensers VC' and VC'' , one of these variable condensers being included in a circuit across one and the other of these variable condensers being included in a circuit across the other of the two condensers C' and C'' .

One embodiment of the third feature of this invention wherein automatic tone control of a superheterodyne receiver is obtained in such manner as to increase the higher audio frequency response when strong signals are received, and to decrease it when weak signals are received, will now be described in connection with Figures 13 and 14 of the accompanying drawings. In this embodiment the receiver comprises the usual pre-selector stage 1, local oscillator and first detector or converter 2, intermediate frequency amplifier 3 and demodulating detector 4. Between the demodulating detector 4 and the usual low frequency amplifier 6 and associated loud-speaker is a variable low pass low frequency filter L. F. The receiver is fitted with the usual A. V. C. system 7 operating, for example, from an intermediate frequency amplifier stage, and effective to control the gain of one or more of the preceding parts of the receiver for anti-fading purposes as in the usual way.

In accordance with this invention unidirectional output voltage from the A. V. C. unit is also applied to control the low pass low frequency filter L. F. so as to cause the upper limiting frequency of said filter to rise in response to a large A. V. C. output and to fall in response to a small one. The low pass filter may be of any known general design, for example as shown in Figure 14 it may comprise a number of inductances L' , L'' and L''' in series in one line and a number of shunt condensers each connected between the other line and one of the inductance terminals, but, in accordance with this invention, these condensers are variable condensers VC' , VC'' , VC''' and VC'''' . A suitable predetermined polarising voltage is applied from a source B through a high resistance R to all these condensers and there is also applied to said condensers, output voltage derived from the A. V. C. unit (7 of Figure 13), the arrangement being such that increase in negative A. V. C. output volts reduces the capacities of the variable condensers in the filter, thereby raising the cut-off frequency.

In a modification illustrated in Figure 13 by the removal of strap SR from terminal t_1 to t_8 , the cut off frequency of the low pass filter is controlled, in dependence upon the amount of high audio frequency present, in such manner as to lower the said cut-off frequency in response to an increase in high audio frequency. As will be appreciated a great part of the noise and interference in a radio receiver is of high audio frequency and therefore this embodiment enables the best compromise to be automatically obtained between the conflicting requirements of maximum fidelity and minimum noise and interference. In this embodiment the A. V. C. unit is not employed to control the filter but is merely utilised in the ordinary well known way for anti-fading gain control. Instead the low pass filter L. F. is controlled in dependence upon the en-

ergy passed by a high pass filter H. F. which is fed from the output from demodulating detector 4. For example as shown in Figure 15 the high pass filter H. F. may consist of a number of series condensers in one line and a number of shunt inductances to the other line and the output of this filter may be fed to a diode or other rectifier circuit RC to produce a unidirectional voltage which, together with a predetermined polarising voltage from source B is applied to the variable condensers in the low pass filter, this low pass filter being as in the first described embodiment. The arrangement is such that increase in high audio frequency in the demodulating detector output produces an increase in the values of the variable condensers in the low pass filter and thereby a reduction in the cut-off frequency of the low pass filter.

In yet another modification illustrated in Figure 13 chain line and by the removal of strap SR from terminal t_1 , or t_8 to t_9 , interference by signals in an adjacent channel is minimised by controlling the cut-off frequency of the low pass filter in dependence upon the amount of adjacent channel energy present. In this embodiment any suitable convenient filter or discriminator circuit DC, for example that illustrated in Figure 6, fed from a convenient intermediate point in the receiver, as shown, between 3 and 4, is adjusted to pass energy corresponding to interfering adjacent channel signals. The voltage thus passed is rectified and the resultant applied together with a polarising voltage to the voltage variable condensers VC' to VC'''' of a low pass filter (such as shown in Figures 14 and 15) connected and arranged as hereinbefore described, the arrangement being such that the cut off frequency of the low pass frequency is lowered in response to an increase in the output from the discriminator.

In yet another embodiment of the invention illustrated in Figure 16 of the accompanying drawings, provision is made for giving what may be termed "automatic contrast amplification." If high audio frequency interference increases, one way of compensating for the loss of intelligibility which would ordinarily result therefrom is to increase the volume of the low notes and the present embodiment accomplishes this result. In this embodiment there is connected across the grid input circuit of a low frequency valve V' for example the low frequency valve which feeds the usual loudspeaker LS, a circuit consisting of a resistance R, a voltage variable condenser VC , a further resistance R' and a polarising voltage source B all in series in the order stated, the polarising voltage source being nearest the cathode of the valve and a blocking condenser and grid leak being inserted in the usual way. The anode of the valve is resistance capacity coupled to the grid circuit of an additional isolator valve V'' whose anode receives anode potential through a circuit XC which may be in the form of a circuit adapted to respond to high audio frequencies or may be in the form of a high pass filter. The anode of the isolator valve is coupled to a diode-resistance circuit DR and the rectified voltage which appears across the resistance of this circuit is fed through any suitable further resistance R'' to the grid side of the voltage variable condenser VC . It will be seen that with this arrangement any increase in high audio interference will produce an increased gain at low audio frequencies thereby increasing

the intelligibility to compensate for the increased high audio interference.

Another very common form of interference which occurs in radio receivers is that known as heterodyne "whistle," i. e. a more or less persistent audio frequency note or whistle due to the interaction of the desired modulated carrier with an adjacent channel modulated carrier. As is well known this common form of interference manifests itself as a disturbing note which is, of course, not always of the same frequency but may vary from time to time, and from station to station. This variation makes ordinary tuned filters very difficult, if not wholly impractical, to apply for the purposes of eliminating the interference since a constant frequency sharply tuned rejector circuit is not sufficient.

The present invention may be applied to obtain reduction or elimination of interference of this nature by providing a rejecting filter which automatically adjusts itself as may be required to the note to be rejected.

One embodiment of this nature as applied to a resistance-capacity coupled low frequency amplifier will now be described in connection with Figure 17 of the accompanying drawings. In this embodiment of the invention the anode end of the usual anode resistance of one low frequency valve V' is coupled to the grid end of the usual grid resistance of the next low frequency valve V'' through three condensers C' , C'' , C''' in series and a resistance R is connected across those two of the three condensers C'' and C''' which are nearer the grid of the second valve V'' . The junction point of these two condensers is connected to the cathode end of the grid resistance of the second valve V'' through a series resonant circuit SR comprising an inductance and a condenser in series. The cathodes of the two valves are each connected to earth through the usual capacity shunted bias resistance. The inductance of the series resonant circuit has, in parallel therewith, a condenser C in series with a diode D' , and a second diode D'' is connected across the condenser of the series resonant circuit. The two diodes have their cathodes connected together and each is in parallel with a load resistance RE' and RE'' . The diode cathode point—which is of course electrically the same as the junction point of the two-load resistances—is connected through a condenser to one side of a voltage variable condenser VC and the other side of this voltage variable condenser is connected to the cathode end of the grid resistance of the second valve through a further condenser. Said other side of the variable condenser is also connected through a resistance R'' (of, for example 10 megohms) to the anode of the diode which is in parallel with the inductance in the series resonant circuit, while the first mentioned side of the said voltage variable condenser is connected through a source of negative potential (not shown) to earth. As will be appreciated the coupling circuit between the two low frequency valves is of the so-called "resistance cancelled "bridge-T" type, and by suitable choice of the component values, the arrangement may be made to give a very low loss, the "cross arm" of the

"bridge-T" throwing negative resistance into the series resonant circuit thus decreasing its losses and giving a sharp absorption effect at the tuned rejector frequency. In effect the voltage variable condenser is included in the series resonant circuit. The arrangement is made such that the series resonant circuit frequency is normally about 9 kc. If, for example, owing to a change in transmitter frequency or frequencies, the interference or "whistle" note becomes higher than 9 kc. the voltage across the inductance part in the series resonant circuit will rise relative to that across the condenser therein; the voltage on the voltage variable condenser will decrease; the capacity of the said voltage variable condenser will decrease; and the tuning of the series resonant circuit will, therefore, alter in the required direction to approach very closely the "whistle" frequency. Should the "whistle" frequency become lower an opposite effect takes place.

It will be appreciated that the feature of the last described embodiment is not limited to the elimination of this particular type of disturbance in audio frequency circuits, nor indeed to audio frequency circuits at all, for the same principle, namely the utilisation of a condenser automatically to vary the resonant frequency of a series resonant circuit in accordance with the frequency of energy fed thereto, may be applied for the elimination of any form of disturbance occurring in a narrow frequency band. In other words, the embodiments just described is a specific but by no means a limiting example of a self-tuning filter the self-tuning action being obtained by phase change brought about in the filter itself by a change in the frequency fed thereto.

Having now particularly described and ascertained the nature of our said invention and in what manner the same is to be performed, we declare that what we claim is:

1. A device for obtaining a variable capacity effect by an applied voltage and including a first electrode comprising a piece of slate having one surface curved and highly polished; a piece of copper foil secured to a flat face of the slate; a piece of polished copper foil in intimate contact with the curved surface of the slate; a fixed auxiliary electrode normally spaced from the polished copper foil and providing the second electrode of the condenser; and means for applying a variable potential between the two pieces of foil.

2. A device for producing a variable capacity effect in response to an adjustable potential comprising a first electrode which includes at least one plate of mineral insulator, a metallic foil secured to one face of the insulator, a second metallic foil secured to the opposite face of the plate, a second electrode consisting of a metallic sheet spaced from said first electrode, and means for varying the potential difference between said foils.
